Primary Examiner — Michael A. Pratt(74) *Attorney, Agent, or Firm* — Filfil IP Inc.; Rami Filfil(57) **CLAIM**

The ornamental design for a packaging container, as shown and described.

DESCRIPTION

FIG. 1 shows a perspective view of a packaging container. FIG. 2 shows a second perspective view of the packaging container in FIG. 1.

FIG. 3 shows a third perspective view of the packaging container in FIG. 1.

FIG. 4 shows a back view of the packaging container in FIG. 1

FIG. 5 shows a front view of the packaging container in FIG. 1

FIG. 6 shows a right-side view of the packaging container in FIG. 1.

FIG. 7 shows a left-side view of the packaging container in FIG. 1.

FIG. 8 shows a bottom view of the packaging container in FIG. 1; and,

FIG. 9 shows a top view of the packaging container in FIG. 1.

The broken lines depict portions of the packaging container that form no part of the claimed design.

1 Claim, 9 Drawing Sheets(56)
